UNITED STATES PATENT OFFICE.

ALFRED EGE, OF SIOUX FALLS, SOUTH DAKOTA.

CONTROLLING DEVICE FOR WINDMILLS.

1,397,802.

Specification of Letters Patent. Patented Nov. 22, 1921.

Application filed January 4, 1921. Serial No. 434,972.

To all whom it may concern:

Be it known that I, ALFRED EGE, a citizen of Norway, residing at Sioux Falls, in the county of Minnehaha and State of South

5 Dakota, have invented certain new and useful Improvements in Controlling Devices for Windmills; and I do declare the following to be a full, clear, and exact description of the invention, such as will enable 10 others skilled in the art to which it appertains to make and use the same.

This invention relates to an improved controlling device for a windmill and one object of the invention is to provide a device 15 so constructed that a windmill may be rendered inoperative when water in a reservoir tank reaches a predetermined level and the windmill then again rendered operative when the water in the tank has decreased in 20 volume to a predetermined extent.

Another object of the invention is to so construct this device that it may be mounted adjacent the base of the windmill and connected with the pump rod and controlling 25 wire of the mill thus permitting the mechanism to be operated by the pump rod and the controlling wire for the windmill drawn upon by being wound upon the drum. In the usual construction of a windmill, there is 30 provided a pump rod which is connected with the pump at the base of the windmill and reciprocated by the windmill. The vane which is carried by a windmill is pivotally mounted and when it is desired to have the 35 pump operate, the vane is left suspending axially of the wheel so that the wheel will be headed into the wind. When it is desired to render the windmill inoperative, a wire will be drawn downwardly to turn the 40 vane radially of the wheel and this will cause the wheel to be swerved as the vane is swung by the wind and the wheel will be prevented from rotating. As will be hereinafter brought out, it is desired by this 45 invention to provide a drum which is movable into and out of operative relation to the operating means connected with the reciprocating pump rod of the mill thus permitting the mill to furnish power for wind- 50 ing the wire upon the drum to turn the vane and render the mill inoperative, the drum being moved into and out of an operative position by shifting means moved through the medium of mechanism controlled by a 55 float in the reservoir tank.

This improved device is illustrated in the accompanying drawings, wherein:

Figure 1 is a top plan view of the improved device.

Fig. 2 is a longitudinal sectional view 60 taken along the line 2-2 of Fig. 1.

Fig. 3 is a fragmentary transverse sectional view taken along the line 3-3 of Fig. 1.

This device will be preferably mounted at 65 the base of the windmill tower adjacent the pump 1 and is provided with supporting bars 2 which extend beneath the reservoir tank 3 and are provided with upturned end portions forming standards 4, the standards 70 4 carrying arms 5 and 6 which extend toward the pump. The arms 6 are connected with the pump by a clamp 7 and the arms 5 form a portion of a yoke, the head 8 of which engages the pump and is connected 75 therewith by clamps 9.

In order to draw upon the wire 10 which extends up through the windmill tower and is used for turning the vane to render the mill inoperative, there has been provided a 80 drum 11 which fits loosely upon a shaft or axle 12 and is provided at one end with clutch teeth 13 adapted to engage co-operating clutch teeth formed upon the hub 14 of a ratchet wheel 15 rigid upon this shaft 85 or axle 12. This shaft or axle 12 will thus be rotated when the ratchet wheel 15 is turning and the drum will be rotated when moved to bring its clutch teeth into operative engagement with the clutch teeth of the 90 ratchet wheel. A rocker arm 16 is loosely mounted upon the shaft 12 and is loosely connected with a pitman bar 17 which will be connected with the pump rod which reciprocates vertically in the tower and operates the pump. This rocker arm 16 carries 95 a pawl 18 for engaging the teeth of the ratchet wheel and imparting rotary movement to the ratchet wheel and a second pawl or latch 19 is mounted upon one of the arms 100 4 and engages the ratchet wheel so that the ratchet wheel may be prevented from rotating in a reverse direction. It will thus be seen that when the pump is in operation and the pitman 17 reciprocated by the pump rod 105 of the mill, rotary movement will be imparted to the ratchet wheel 15 and as soon as the drum is moved into engagement with the hub of the ratchet wheel, the drum will be rotated and the wire wound upon the 110

drum thus turning the vane of the windmill to render the windmill inoperative. The mill will then discontinue to operate and rotary movement of the ratchet wheel and 5 drum will be discontinued.

It is desired to have the drum move to render the mill operative or inoperative according to the level of the water in the tank or reservoir 3 and in order to do so, there 10 has been provided a float 20 which is positioned in the tank and will be raised or lowered according to the level of the water. This float is provided with a standard 21 which extends upwardly through the tank 15 and carries a side arm 22 which is connected with the upper end of a rack 23 slidably mounted in a track 24 secured to the side of the tank. This rack engages a gear or pinion 25 which may be termed a toothed disk 20 and is rotatably mounted by means of a shaft or axle 26. A striker bar 27 which is provided at one end with a weight 27' is loosely mounted upon this shaft or axle 26 and is positioned upon the shaft so that 25 when the gear or disk 25 rotates, the abutment pin 28 which fits in a selected opening 28' will engage the striker bar and impart swinging movement to the same. It will thus be seen that movement of the striker 30 bar is controlled by rotation of the disk and this disk is rotated through the medium of the rack bar, the direction in which the float is moving controlling the direction in which the disk rotates.

35 In order to shift the drum from the inoperative to the operative position and return the drum to the inoperative position, there has been provided a drum shifting device having a rocker sleeve 29 which is rotatably 40 mounted upon a spindle 30 carried by a supporting arm or bracket 31. A collar 32 is mounted upon the drum and provided with side pins 33 engaged by the forks 34 of the sleeve so that when the sleeve is rotated, the 45 drum will be moved longitudinally. A handle or turning arm 35 extends from this rocker sleeve into the path of movement of the striker arm where it may be engaged by the striker arm and the sleeve thus rotated 50 to impart longitudinal sliding movement to the drum.

When this device is in operation, the pitman rod 17 reciprocates and the pawl 18 turns the ratchet wheel 15. As the reservoir 55 tank 3 fills, the float moves upwardly and when the abutment pin 28 engages the weighted end portion of the striker, the striker will be swung until the weighted end passes the upper dead center. The weight 60 will cause the striker bar to fall downwardly and when the striker hits the lever handle 35, the rocker sleeve will be rotated to move the drum longitudinally and bring the clutch teeth thereof into operative engagement 65 with the clutch teeth of the ratchet wheel.

The drum will then be rotated until the wire 10 has been wound upon the drum a sufficient amount to draw upon the wire and throw he windmill out of operation.

When the water in the reservoir decreases 70 in volume, the gear or disk 25 will be rotated in an opposite direction to its previous location and as the abutment pin moves downwardly, it will engage the unweighted end portion of the striker bar and move the 75 striker bar until the weight passes the upper dead center. The striker bar will then turn upon its pivot and the unweighted end portion will strike the lever handle 35 thus turning the rocker sleeve and moving the 80 drum to bring the clutch teeth out of engagement. This will release the drum and the wire can then move upwardly to permit the windmill to resume operation. It will thus be seen that there has been provided a 85 mechanism so constructed that the windmill may be rendered inoperative when the water in the reservoir reaches a predetermined level and the windmill may then be returned to the operative position when the water has 90 decreased a predetermined extent.

I claim:

1. In a pump operating structure, a water tank, a float in said tank, a slidably mounted rack connected with said float and moving 95 with the float, a rotatably and slidably mounted drum having a clutch element at one end, a rotatably mounted driving element having a clutch element for engagement by the clutch element of said drum, 100 a gear rotatably mounted and meshing with said rack, means to be actuated from a pump operating mechanism, operatively associated with the driving element for imparting rotary movement to the same when the pump 105 is in operation, a flexible control element for the pump operating mechanism wound upon said drum, and means to slide the drum longitudinally comprising a rocker sleeve, forks extending from the sleeve and engaging the drum, a lever arm extending from the sleeve, a striker bar pivotally mounted and having one end portion weighted and extending for engaging the lever arm, and a pin extending from said gear for engaging 110 the unweighted end portion of said striker bar.

2. In a pump operating and controlling structure, a tank, a float in said tank, a rack actuated from said float, a gear rotated by 120 said rack, a pivotally mounted striker bar having one end portion weighted, an abutment extending from the gear for engaging the striker bar and swinging the bar upon its pivot, a rotatably and slidably mounted 125 winding drum having clutch teeth at one end, a ratchet wheel having clutch teeth for engagement by the teeth of said drum, a rocker arm, a rod for connection with a pump rod pivotally connected with said 130

- rocker arm, a pawl carried by said rod and engaging said ratchet wheel, and means for shifting said drum longitudinally comprising a rocker sleeve, forks extending from 5 said sleeve and engaging the drum, and a lever arm extending from the sleeve for engagement by said striker bar.
3. In a pump operating and controlling structure, a tank, a float in said tank, a winding drum rotatably and slidably mounted, a rotatably mounted driving wheel, means for imparting rotary movement to the driving wheel adapted for operative connection with a pump rod, coöperating clutch elements 10 carried by said drum and driving wheel, a striker means for shifting the drum longitudinally including an actuating handle extending for engagement by said striker, and means actuated from said float for imparting movement to said striker.
4. In a pump operating and controlling structure, a tank, a float in said tank, a rotatably and slidably mounted drum, a driving wheel for said drum, coöperating clutch 15 elements carried by the drum and wheel, operating means for rotating said wheel adapted for connection with a pump rod, a shifting element for moving the drum into and out of engagement with the wheel including 20 an operating handle, a pivotally mounted
- striker for engaging said handle, a rotatably mounted disk having an extension for engaging said striker and imparting movement to the same, and means moving with said float and imparting rotary movement 35 to said disk as the float moves.
5. In a pump operating and controlling structure, a tank, a float in said tank, control wire tightening means including actuating means adapted for connection with a pump rod, a relatively stationary clutch element and a relatively movable clutch element, shifting means for the movable clutch element including a handle, a striker for engaging the handle and imparting movement 40 to said shifting means, and means actuated from said float for imparting movement to said striker.
6. In a pump operating and controlling structure, a tank, a float in said tank, a wire 45 tightening element, operating means therefor including an element for connection with a pump rod, shifting means for moving the wire tightening element into and out of engagement with the operating means, and means actuated from said float for imparting movement to said shifting means.

In testimony whereof I have hereunto set my hand.

ALFRED EGE.
